UNITED STATES PATENT OFFICE.

ALICE BURCHELL, OF MAYFIELD, ENGLAND.

CHILD'S COMBINATION-COT ADAPTABLE AS PLAY-PEN, &c.

1,354,088.

Specification of Letters Patent. Patented Sept. 28, 1920.

Application filed March 30, 1920. Serial No. 369,989.

To all whom it may concern:

Be it known that I, ALICE BURCHELL, a subject of the King of Great Britain and Ireland, and a resident of Mayfield, county 5 of Sussex, England, have invented a certain new and useful Improvement in Children's Combination-Cots Adaptable as Play-Pens, or as Means to Facilitate Walking, or for other Purposes, of which the 10 following is a specification.

The invention provides a child's combination cot, adaptable as a play pen, or as means to facilitate the child walking, or as a seat and table receptacle, or as a cradle, 15 or as some or all of these.

An important feature of the invention consists in providing in the cot a bed capable of being wholly or partly withdrawn from its normal position so that it uncovers 20 the whole or part of the floor area formerly covered by it.

To facilitate a child learning to walk, I provide within the cot framing a handle bar or its equivalent, conveniently removable and adjustable in position, whereby, 25 when the bed is withdrawn, the handle bar and cot framing serve to steady the child and prevent it from falling.

A removable seat and hinged table may 30 also be included as accessories to the cot.

Further features of the invention are the devices for preventing the cot from lurching backward when the child is trying to walk, and for applying a resistance to the 35 cot's motion suitable for the child's strength. These devices may include casters provided with ratchet gear and adjustable brakes.

Another feature of my invention is the provision of adjustable rockers, whereby the 40 cot may serve as a cradle.

The accompanying drawings illustrate, by way of example, one embodiment of the invention. In these drawings:—

Figure 1 is a plan view of the cot.

45 Figs. 2 and 3 are side and end views respectively, showing more clearly the means for mounting the collapsible bed, adjustable handle bar, table and rockers.

Figs. 4 and 5 show the ratchet gear for 50 the casters; and,

Figs. 6 and 7 the brake device for the same.

Referring to the drawings, the seat 1 is provided at one end of the cot, this seat being 55 provided with legs 2 of metal to engage

over the lower bar 3 of the cot framing. At the sides and rear of the seat, padded boards 4, 4, 4 are provided, these being removable by means of turnbuckles 5 which engage the adjacent rails of the framing. When 60 the padded boards are removed, the seat 1 may be removed from the cot by raising the legs 2 from the bars on which they rest and are steadied by the depending lugs 2'.

I may, if desired, mount a seat externally 65 on the framing. Below the seat is mounted the roller bed 6, this being of mackintosh cloth, for example, and being spring-controlled somewhat in the manner of a roller blind.

As seen in Figs. 1 and 2, the bed, when extended, conveniently passes up behind the seat and forms a horizontal bed secured by hooks 7.

From the above, one feature of the invention is made clear. The rolled bed, with or without the seat, may be withdrawn so that it uncovers the area below the cot. The latter may thus serve as a play pen or safe 75 enclosure for a child.

For teaching the child to walk, the bed is released and the child stands within the cot with its hands on a handle bar 8, which may be provided with a rubber covering, and this bar is so mounted that it may have 80 considerable adjustment in position. Two slotted arms 9 are therefore provided, these arms being clampable at various angles and elevations by means of vertically guided plates 10 to which the arms are pivotally 85 connected in such manner that winged nuts 11 may tighten bolts 12 passing through the slots in the arms and through the plates.

The cot may be provided with means for facilitating its motion when the handle bar 90 8 is in use. I may use casters 8' (Figs. 4-7) and may provide a ratchet gear (Figs. 4, 5) and a brake device (Figs. 6, 7) if desired. The ratchet gear prevents backward movement of the cot, and the brake device gives 95 the cot a resistance to motion suitable for the child's strength.

Instead of casters I might provide other devices (so-called "domes of silence," for example) and non-return and braking devices engaging the floor.

A hinged table 13, 13' may also be provided at a convenient height for a child sitting on the seat 1. The two halves of the table may overlap as shown in Fig. 3, 110

but normally are turned up, as shown in dotted lines in this figure, and are held from falling down by any suitable device (e. g. elastic bands around each flap and the adjacent cot rails).

- Referring now to the details of the caster mountings, it will be seen from Figs. 4, 5 that the ratchet 14 engages the teeth 15 in the wheel as soon as the eccentrically mounted lever 16 is turned upwardly. The helical spring 17 then raises rod 18 and the ratchet 14 is free to fall by gravity. The reverse movement of lever 16 frees the ratchet by swinging it about its pivot 17.
- 10 The brake gear shown in Figs. 6, 7 comprises a rod 18, on a bottom flange of which is a rubber pad 19. The spring 20 tends to keep the brake off the wheel, but turning of the knob 21 causes its stem 22 to take various positions on the cam surface 23 and the brake rod 18 is thus caused to approach or recede from the caster wheel whereby the pressure thereon may be regulated.
- 15 Another adjustment I may make to the cot is raising its walls by means of an auxiliary framing mounted above the existing

framing. This provides convenient heights of rail for children of various ages.

Finally, the cot may be utilized as a cradle by providing it with hinged rockers 19' 30 (Figs. 1, 2) which take the whole weight of the cot when they are turned down, and when turned up may be held secure from falling by any suitable device, such as elastic bands.

35

I claim:—

A device of the class described including in combination, an inclosure frame, a removable bottom therefor, a seat adapted to be supported on the side rails of said inclosure frame and at one end thereof, cushions detachably carried by the side walls of the inclosure frame adjacent the seat position, and a table located adjacent the seat position and consisting of swinging 45 leaves hinged to the opposite side walls of the inclosure frame.

In testimony whereof I have hereunto affixed my signature this 13th day of March, 1920.

ALICE BURCHELL.
